NARROW WARE LOOM SHUTTLE

Lewis O. Waterhouse, Oxford, Mass., assignor to Crompton & Knowles Corporation, Worcester, Mass., a corporation of Massachusetts

Application July 17, 1956, Serial No. 598,413

11 Claims. (Cl. 139—199)

This invention relates to improvements in shuttles for narrow ware looms and it is the general object of the invention to construct a shuttle that is a composite of units easily separable with respect to each other, whereby one of said units which supports a quill can be rapidly removed and have substituted therefor another similar unit having a quill of different size while still retaining the same shuttle body or runner unit.

Shuttles for narrow ware looms are usually made from a single block of wood requiring several expensive wood-working operations to obtain the proper shape. The exterior of the shuttle must be highly polished so as not to injure or break the warp threads between which it passes. Also, the bow of the shuttle is made of such thickness for strength purposes that the quill used is necessarily short. Moreover, it has been necessary in the past to provide the shuttle with a warp spreader wire to prevent contact of the bow of the shuttle with the warp threads while the shuttle is entering or leaving the warp shed. It can readily be appreciated that the above described shuttle requires much attention and care in its manufacture.

It is an important object of the invention to provide a shuttle consisting of runner, bow and spreader units, these units being easily manufacturable, separable, simple and inexpensive in their construction, and capable of ready assembly.

Another object of the invention is to eliminate the need of highly polishing the entire shuttle by making the third unit which spreads the warp with only a small exterior surface in need of polishing and of a configuration greater than that of the remaining units, this third unit being preferably the only unit contacting the warp threads while the shuttle passes between them.

Still another object of the invention is to make the bow unit of a comparatively small diameter tube bent U-shaped to have legs which can be inserted into the runner unit adjacent its ends, thereby defining a larger quill opening or chamber than is possible with the ordinary narrow ware shuttle.

A specific object of the invention is to make the bow unit in a manner to include a support for the quill one end of which is pivotally mounted on one of the aforesaid legs and provide lock means on the other leg for the other end of said support anchor pins and eyelets for thread tensioning springs, a self-retaining slide eyelet wire support, and glide means for said springs to facilitate the construction and expansion thereof into and out of said bow.

Further, another object of the invention is to provide the shuttle with a single lock means unit mounted on the runner unit and effective to firmly lock the tubular bow unit to the runner unit and also effective to contact the warp thread while weaving to spread them in an up and down direction to prevent contact of the quill and the tubular bow and runner units with the warp threads.

Other objects of the invention will appear hereinafter, and for a further understanding of the invention

2

reference is made to the accompanying drawings which illustrate by way of examples two embodiments of the invention and in which:

Fig. 1 is a plan view of a shuttle showing the preferred form of the invention,

Fig. 2 is a front elevation of the shuttle looking in the direction of arrow 2, Fig. 1,

Fig. 3 is an end elevation of the shuttle looking in the direction of arrow 3, Fig. 1, and includes a sectional portion of the usual shuttle block with the shuttle driving pinion thereon,

Fig. 4 is a horizontal section on line 4—4, Fig. 2,

Figs. 5, 6, 7 and 8 are detailed vertical sections taken respectively on lines 5—5, 6—6, 7—7, and 8—8 of Fig. 4,

Fig. 9 is a detailed vertical section taken on line 9—9, Fig. 7,

Fig. 10 is a detailed vertical section on line 10—10, Fig. 4,

Figs. 11 and 12 are views in cross section similar to a portion of Fig. 3 illustrating the manner in which the aforementioned units are locked together, and

Fig. 13 is a view similar to a portion of Fig. 3 but showing a modification of the invention.

With reference to the drawings, the shuttle is generally indicated at 1 and has a runner unit generally indicated at 2 having a body or base 3 with the usual guide groove 4 and gear rack 5 to cooperate respectively with the usual shuttle block 6 and pinion 7, see Fig. 3, to reciprocate the shuttle during weaving between top and bottom sheets WT and WB respectively of warp threads, see Fig. 3. Detachably mounted on the base 3 is a substantially U-shaped tubular bow unit generally indicated at 8. Also detachably mounted on the base 3 is a single lock means unit generally indicated at 9 to coat with the bow unit 8 to lock the latter to the base 3.

As shown in the drawing the bow unit 8 comprises a light-weight tubular body 11 having right and left legs 12 and 13 respectively, see Figs. 1 and 4, joined integrally with an arch or shuttle nose 14 to form a generally U-shaped bow. Collars 15 and 16 are held fast to the leg 12 by pins 17 and 18 respectively and are spaced from each other along the leg 12 to receive snugly between them the loop 19 of a support member 21 on which the quill 22 is rotatably mounted. The loop 19 surrounds the leg 12 and has pivotal relationship therewith.

The left-hand end 23 of member 21, Fig. 4, fits into a key slot 24 in a collar or socket member 25 fixed to the leg 13 by a pin 26. Slot 24 has an enlarged end 26 connected by a reduced neck 27 to a semi-circular socket 28 to receive the end 23 of member 21. The neck 27 is of less width than the diameter of member 21. Areas 31 and 32 on collar 25 adjacent to neck 27 act to positively confine the end 23 to collar 25. To remove the quill 22 it is merely necessary to apply pressure to its left underside, Fig. 1, thereby forcing the end 23 upwardly, Fig. 9, through neck 27 to spread areas 31 and 32 apart. Continued upward movement of the quill 22 moves end 23 out of enlarged end 26 of slot 24 and away from collar 25 due to pivoting of loop 19 around leg 12. Conversely, it is only necessary to reverse the procedure outlined above to lock a quill to the shuttle. Collars 15, 16 and 25 are preferably made of nylon but this is not essential to the invention, although some inherent resilience of collar 25 is desirable.

Nose 14 is made with two holes 33 and 34 to receive respectively legs 35 and 36 of a support wire 37 having slidably mounted thereon a sliding guide eyelet 38 to receive the filling thread F. Legs 35 and 36 have bent end portions 39 and 41 respectively to hold wire 37 to the nose 14. Wire 37 is made of spring material and in order to remove or insert wire 37 into holes 33 and 34, legs 35 and 36 are moved toward each other to align

65
70

end portions 39 and 41 with holes 33 and 34, after which the wire 37 can be removed, or the legs 35 and 36 released, as the case may be.

The filling thread F passes from the quill 22 through guide eyelet 38, thence through eyelets 42 and 43, and then out through eye-bushing 44 to the selvage of the fabric (not shown). Eyelet 42 is attached to one end of a tension spring 45 which passes through a hole 46 in tubular body 11. Spring 45 is located inside leg 12 and its other end is anchored to pin 47 fixed to leg 12 adjacent the end of the latter, see Fig. 4. Also, eyelet 43 has a tension spring 48 attached thereto which passes through a hole 49 in tubular body 11. Spring 48 is located inside of leg 13 and its end is anchored to pin 51 similar to pin 47 fixed to leg 13. Formed integrally with legs 12 and 13 are guide lips 52 and 53 for springs 45 and 48, respectively. These lips are curved toward each other in a manner to guide the springs into and out of legs 12 and 13. Eyelets 42 and 43 are larger than holes 46 and 49 respectively to prevent contraction of springs 45 and 48 into legs 12 and 13 respectively.

Runner unit 2 has right and left-hand holes 54 and 55 respectively to receive a substantial part of legs 12 and 13 respectively, see Fig. 4. Held on runner base 3 by screws 56 and 57 is the single lock means or spreader unit 9 having a relatively thin, flat body member 58. Member 58 has an upper edge surface 59 and a lower edge surface 61, these surfaces being substantially parallel to each other. Surfaces 59 and 61 have extending from their right-hand ends thereof, Fig. 2, converging surface portions 62 and 63, and from their left-hand ends similar surface portions 64 and 65 respectively. These converging surfaces form the pointed end portions 65' and 66 of the base member 3.

Member 58 has a pair of holes 67 and 68 through which the legs 12 and 13 respectively pass. Countersunk holes 69 and 71 in member 58 receive the screws 56 and 57 respectively which enter pilot holes 72 and 73 respectively in runner 3. A central aperture 74 in member 58, Fig. 4, has passing therethrough the usual drag brake 75 and spring 76 therefor attached in the usual manner to the runner unit 2.

As seen in Fig. 11 the axis *a* of pilot hole 72 is slightly below the axis *b* of countersunk hole 69 such that holes 69 and 72 are slightly misaligned. Likewise the pilot hole 73 and the countersunk hole 71 are also slightly misaligned. With the parts loosely assembled as viewed in Fig. 11 the screw 56 will enter holes 69 and 72 angularly with respect to member 58 and runner base 3 and will be forced downwardly due to misalignment of holes 69 and 72. Continued insertion of the screw 56 will force member 58 downwardly and to the left, Fig. 12, such that hole 67 will clamp or pinch the leg 12 and hold the latter in fixed relationship to the runner base 3. In similar manner leg 13 will be clamped to runner base 3. Upon completion of insertion of screws 56 and 57 all three of the units 2, 8 and 9 will be simply yet effectively locked with respect to each other, as viewed in Fig. 3.

In the modified form, Fig. 13, a runner unit 80, a lock unit 81 and a tubular bow unit 82 are similar to the corresponding parts of the preferred form of the invention. Unit 80, however, has along the entire length of its lower part a surface 83 slightly oblique with respect to surface 84 on unit 80. Countersunk hole 85 in unit 81 and pilot hole 86 in unit 80 are normal to surface 83. Screw 87 holds unit 81 detachably mounted on unit 80. When screw 87 is tightened surface 83 will cause unit 81 to tilt, whereby hole 88 in the lock unit 81 will clamp or pinch tubular body unit 82 to hold the latter in locked relationship with respect to runner unit 80. The arrangement shown in Fig. 13 can be used at each end of the runner unit 80.

From the foregoing description it is seen that the invention provides a shuttle having units 2, 8 and 9 com-

plete in themselves wherein unit 9 is secured to unit 2 in such a manner as to hold all three units effectively in locked relationship with each other. To remove the bow unit 8 it is only necessary to loosen screws 56 and 57 from the full to the dotted line position and move unit 8 to the left from the full to the dotted line position, see Fig. 3. Unit 8 may be removed while the runner 3 is either on or off the shuttle block 6. Moreover, any unit may be changed with respect to the remaining units by complete removal of the screws 56 and 57. Unit 8 pivotally supports quill pin member 21 which can be also positively locked thereto. Tension springs 45 and 48 are guided into body 11 of unit 8 and upon removal of the quill 22 said springs contract into legs 12 and 13 but cannot fall loose due to the connections at each end of the springs. Guide lips 52 and 53 are made in such manner as to eliminate sharp corners to prevent entanglement or catching of the springs on the tube 11. Wire 37 is supported on arch 14 and because of its inherent resiliency and the particular manner in which it is supported it is free to pivot relatively to the arch to find a position best suited for supporting the guide eyelet 38.

It is apparent that certain changes may be made without departing from the spirit and scope of the invention, and having fully described and ascertained the nature of the invention, what is claimed is:

1. In a narrow ware shuttle, an elongated runner unit having provision for support on a shuttle block and having two parallel holes therein, one near each end of the runner, a U-shaped bow unit for support of a weft supply having the opposite parallel sides thereof inserted into said holes in the runner unit, a bow holding and warp spreader unit having holes therein through which said parallel sides pass, and means extending through the spreader unit into the runner unit securing the spreader unit to the runner unit and forcing the spreader unit against said parallel sides to hold the bow unit in fixed position on the runner unit.

2. The shuttle set forth in claim 1 wherein said means is removable to enable the holes in the spreader unit to align with the adjacent holes in the runner unit, whereby the bow unit can be removed from the runner unit.

3. The shuttle set forth in claim 1 wherein the runner unit has a surface oblique to the sides of said bow unit and said means causes the spreader unit to lie against said oblique surface.

4. The shuttle set forth in claim 1 wherein the spreader unit has openings therein and said means are screws passing through said openings into pilot holes in the runner unit at a distance from the adjacent side of the bow unit different from that of the corresponding opening in the spreader unit.

5. The shuttle set forth in claim 4 wherein the openings in the spreader unit are countersunk to receive complementarily-shaped heads on the screws, the screw heads by their engagement with said openings forcing the spreader unit laterally relative to the bow unit when the screws are tightened into the runner unit.

6. The shuttle set forth in claim 1 wherein a brake for a weft supply on the bow unit is pivoted on the runner unit and extends through a central aperture in the spreader unit and the means are removable to enable the bow and spreader units to be removed from the runner unit while the brake is pivoted on the latter unit.

7. In a bow unit for a narrow ware shuttle having a runner unit, said bow unit including a one-piece tube bent U-shaped having an arch and parallel legs adapted for connection with the runner unit, a quill pin having an eye on one end thereof encircling and pivoted on one of said legs, means on said one leg preventing said eye from moving therewith, and a socket member fixed on the other leg having a slot to receive and have a close fit with the other end of said quill pin.

8. The unit set forth in claim 7 wherein the socket

member is made of resilient material and the slot has a reduced neck of less width than the thickness of the pin, said slot beyond the neck being wider than the latter to receive said other end of the pin after it has been forced through said neck.

9. In a bow unit for a narrow ware shuttle having a runner unit, said bow unit including a one-piece tube bent U-shaped having an arch and parallel legs adapted for connection with the runner unit, a tension spring anchored to the end of each leg remote from the arch and extending to and extensible through an opening in the leg, a weft guide eye secured to each spring held normally against the leg therefor by its spring, each of said legs having an opening therein for the corresponding spring facing the other leg, and a lip for each opening integral with the corresponding leg along which the associated spring slides when extended toward the other leg.

10. In a bow unit for a narrow ware shuttle having a runner unit, said bow unit having a weft guide eye thereon and including a one-piece tube bent U-shaped having an arch and parallel legs adapted for connection with the runner unit, and a support for said eye comprising a

resilient wire having a part along which the eye can slide and a leg at each end of said part having a bent end portion extending through a hole in said arch and into the latter to be held against accidental removal by engagement of said bent ends with the interior of the tube, said legs due to their resilience being bendable toward each other to cause said bent ends to register with their respective openings for easy removal or insertion of the support from the arch.

11. The unit set forth in claim 10 wherein said bent ends and holes in the arch permit a limited angular movement of the legs and said part of the wire relative to the plane of said tube.
